(57) **CLAIM**

The ornamental design for the front panel for storage, as shown and described.

DESCRIPTION

FIG. 1 is a top perspective view of the front panel for storage showing our new design, the dashed lines indicating storage which forms no part of our design;

FIG. 2 is a front elevational view thereof;

FIG. 3 is a sectional view along the line 3—3 of FIG. 2;

FIG. 4 is a rear elevational view thereof;

FIG. 5 is a left-side elevational view of one side thereof;

FIG. 6 is a right-side elevational view of the other side thereof;

FIG. 7 is a top plan view thereof; and,

FIG. 8 is a bottom plan view thereof.
